(57) **CLAIM**

The ornamental design for a nitric oxide generation system, as shown and described.

DESCRIPTION

FIG. 1 is a side front perspective view of one embodiment of a nitric oxide generation system showing the claimed design;

FIG. 2 is a side rear perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof; and,

FIG. 8 is a top view thereof.

The broken lines in the figure depict portions of the nitric oxide generation system that form no part of the claimed design.
